UNITED STATES PATENT OFFICE.

GEORGE A. DICKINSON, OF DAVENPORT, IOWA.

ADJUSTABLE SASH WEIGHT.

Application filed August 10, 1922. Serial No. 530,962.

To all whom it may concern:

Be it known that I, GEORGE A. DICKINSON, a citizen of the United States, residing at Davenport, in the county of Scott and State 5 of Iowa, have invented certain new and useful Improvements in Adjustable Sash Weights, of which the following is a specification.

This invention relates to window sashes, 10 and the primary object of the invention is to provide an improved sash weight embodying novel means for permitting the weight of the body thereof to be conveniently changed to conform to the weight of the 15 window sash to be balanced.

Another object of the invention is the provision of an improved sash weight embodying a body having a longitudinally extending pocket formed therein opening out 20 at one longitudinal face thereof, the pocket being adapted to receive small weight segments to permit the weight of the body to be changed.

A further object of the invention is to 25 provide novel means for associating the small weight segments with the body of the sash weight so as to permit the weight segments to be readily and quickly associated with or removed from the body of 30 the sash weight and to prevent accidental displacement of the segments when the sash weight is in use.

A further object of the invention is the provision of an improved adjustable sash 35 weight embodying a body having a longitudinally extending pocket formed therein opening out at one longitudinal face thereof for the reception of small weight segments, and means formed on the lower end thereof 40 for detachably supporting a relatively large weight segment, the body of said sash weight being so constructed as to permit the simultaneous use of any number of small weight segments and the relatively large weight 45 segment.

A still further object of the invention is the provision of an adjustable sash weight of the above character, which will be durable and efficient in use, one that will be 50 simple and easy to manufacture, and one which can be placed upon the market at a reasonable cost.

With these and other objects in view, the invention consists in the novel construction, arrangement and formation of parts, as will be hereinafter more specifically described,

claimed and illustrated in the accompanying drawings, forming a part of this specification, in which drawing:

Figure 1 is a fragmentary perspective 60 view of a window frame showing the improved sash weight incorporated therewith.

Figure 2 is an enlarged perspective view of the improved sash weight showing the relatively large weight segment connected to 65 the body of the weight and one of the relatively small weight segments positioned in the pocket formed in the body of the weight.

Figure 3 is a fragmentary detail perspective view of the lower portion of the body 70 of the improved sash weight.

Figure 4 is a detail perspective view of the relatively large weight segment.

Figure 5 is an enlarged fragmentary longitudinal section through the upper end of 75 the body portion of the sash weight, showing the means of connecting the pulley for the sash cord therewith.

Figure 6 is a detail plan view of one of 80 the relatively small sash weight segments.

Referring to the drawings in detail, wherein similar reference characters designate corresponding parts throughout the several views, the letter A generally indicates the improved sash weight and B a 85 window frame or casing, with which it can be associated.

The window frame or casing B forms no part of the present invention but has merely been shown to illustrate the use of the improved weight, and as shown in the drawings, the casing or frame B includes the usual pulley stiles 10, which support the pulleys 11 and 12 for the sash cord 13, on which the sash weight A is hung. The 95 sashes 14 and 15 are mounted in the usual manner within the window frame B.

The improved sash weight A comprises a body 16 having its upper end slotted or bifurcated as at 17 for the reception of the pulley 18 around which is adapted to be trained the sash cord 13 for the sashes 14 and 15. A suitable pin 19 is carried by the upper end of the body 16 for rotatably supporting the pulley. A longitudinally extending pocket 20 is formed in the body 16 below the bifurcated or slotted portion 17 and this pocket opens out through one of the longitudinal side faces of the body as clearly shown in Figures 2 and 3 of the drawings. It is also preferred that the said pocket open out through the lower end of the body, 110

and this pocket defines a rear wall 21, side walls 22, and a top wall 23. The lower terminals of the side walls 22 are provided with inwardly extending lugs 24 which form a support for the relatively large weight segment C and a stop for the relatively small weight segments D. It is preferred that the upper edges of the lugs 24 be provided with semi-circular notches 25 for forming bearings, as will be hereinafter more fully described. The lower faces of these lugs, as well as the side walls 22 terminate in an arcuate plane to form arcuate bearing faces 26, the purpose of which also will be hereinafter more fully described.

Disposed within the pocket 20 and formed integral with or connected to the rear wall 21 is the longitudinally extending centrally disposed guide rail 27. This guide rail is 20 of a dove-tail shape in transverse section and terminates short of the top wall 23 of the pocket 20 as indicated by the reference character 28. This guide rail 27 can extend to the extreme lower end of the pocket 20 25 if so desired, as clearly shown in Figure 3 of the drawings.

The relatively large segmental weight C includes a solid body 30 having its upper edge concaved as at 31 which conforms to 30 the arcuate bearing surfaces 26 of the lower end of the body 16 of the sash weight A. The upper end of the relatively large weight segment C is provided with a pair of spaced upstanding arms 32 which are adapted to 35 fit within the pocket 20 in facial abutment with the lugs 24. The upper terminals of the arms 32 have their outer side faces provided with semi-cylindrical bearing pins 33, which are adapted to fit within the semi-circular shaped bearing notches 25 formed on the bearing lugs 24. Thus, in associating the segmental weight C with the body 16 of the sash A, the segment C is held at right angles to the body 16 and pushed inwardly until the semi-cylindrical bearing pins 33 rest above the bearing notches 25 at which time the weight segment C can be 40 swung down parallel with the body 16 and the semi-cylindrical bearing pins 33 will drop into the semi-circular bearing notches 25. The connection of the segmental weight C of course, adds weight to the sash weight A as is readily apparent.

The relatively small weight segments D 55 each consist of a flat body 40 having the inner edge thereof provided with a dove tailed groove 41 for the reception of the dove tailed guide rail 27. In associating a relatively small weight segment D with the body 16 of the sash weight, the same is disposed in the upper end of the pocket 20 and pushed inwardly until the dove tailed groove 41 is directly above the rail 27, at which time the weight can be pushed downward 60 within the pocket on the rail 27. It can be

seen that the upper faces of the lugs 24 will form stops for the relatively small weight segments D and thus prevent the same from falling out of the pocket 20. It is apparent, of course, that outward movement of 70 the weight segments D through the open face of the body 16 is prevented owing to the shape of the guide rail 27.

It is also apparent that the displacement of the weights D from out of the pocket will 75 be prevented, by nails inadvertently driven through the stile 10, in that these weights will frictionally bind on the rail 27, when pressure is applied to the outer end thereof as is readily apparent.

It also can be seen, of course, that when weight segments D are associated with the body 16, weight is added to the sash weight A.

In use of the improved sash weight, the 85 same is associated with the sash cord 13 by training cord about the pulley 18 and if the body 16 is not of sufficient weight to balance the sashes 14 and 15, the weight segments D are added thereto by sliding the same within the pocket. As many weight segments can be added to the body 16 as is found necessary and if it is found that a number of the weight segments are 90 not sufficient to properly balance the sashes, the weight segments D can be removed and the relatively large weight segment C associated with the lower end of the body 16 after which weight segments D can be 95 added thereto as found necessary.

From the foregoing description, it can be seen that an improved sash weight has been provided, in which the weight of the body thereof can be readily adjusted in a 100 convenient and expeditious manner when found necessary or desirable.

Changes in details may be made without departing from the spirit of this invention; but,

I claim:

1. A sash weight comprising a body having a longitudinally extending pocket formed therein opening out through one longitudinal face of the body, and a longitudinally extending guide rail disposed within said pocket, the upper end of said guide rail being spaced from the upper wall of said pocket, and weight segments slidably and detachably mounted upon said rail.

2. A sash weight comprising a body having a longitudinally extending pocket formed therein opening out through one longitudinal face thereof, stops carried by the lower end of the body and disposed within the pocket, and a guide rail extending longitudinally of the pocket, the upper end of the guide rail being spaced from the upper wall of the pocket, and segmental weights slidably and detachably mounted

upon said rail and adapted to rest upon said stop.

3. A sash weight comprising a body having its upper end bifurcated and provided with a longitudinally extending pocket disposed below the bifurcated end opening out through one longitudinal face of the body, a sash cord pulley disposed within the bifurcated portion of the body, weight segments adapted to be disposed within said pocket, and a relatively large weight segment adapted to be associated with the lower end of the body, and lugs formed on the body adapted to extend within the pocket for forming stops for the weight segments disposed within the pocket, and a support for the weight segment associated with the lower end of the body.

4. A sash weight comprising a body having a longitudinally extending groove formed in one face thereof and opening out through the lower end thereof, combined stop and bearing lugs carried by the lower end of the body extending into the groove, a longitudinally extending guide rail carried by the rear wall of the groove, relatively small weight segments adapted to be positioned within the groove and slidably and detachably associated with the rail, the lugs forming stops for the weight segments, and a relatively large weight segment detachably associated with the lower end of the body provided with means for engaging said lugs.

5. A sash weight comprising a body having a longitudinally extending groove formed in one face thereof and opening out through the lower end thereof, a guide rail carried by the rear wall of the groove and terminating short of the upper wall of the groove, segmental weights adapted to be disposed within the groove having guide slots formed in their rear edges for receiving a guide rail, the upper end of the guide rail being spaced from the upper wall of the groove substantially, the thickness of a weight segment.

6. A sash weight comprising a body having a longitudinally extending groove formed in one face thereof and opening out through the lower end thereof, inwardly extending lugs formed on the side walls of the groove having semi-circular bearing notches formed in the upper edges thereof, a dove-tail shaped guide rail formed on the rear wall of the groove, relatively small weight segments adapted to be placed in the groove having dove tailed grooves formed in their rear faces for receiving the rail, the rail terminating below the upper wall of the groove, and a relatively large weight segment for association with the lower end of the body having spaced arms formed thereon, and outwardly extending semi-cylindrical bearing pins for detachably fitting within said bearing notches.

GEORGE A. DICKINSON.
